STOKER

Clifford E. Harrison, Philadelphia, Pa., assignor
to American Engineering Company, Philadelphia, Pa., a corporation of Pennsylvania

Application January 16, 1935, Serial No. 2,033

5 Claims. (Cl. 110—44)

This invention relates to an improved grate construction for stoker furnaces, which enables efficient burning of all grades of fuel.

In the prior art constructions air is emitted to the fuel bed through a series of superimposed tuyères having air passages provided around the sides and rearwardly disposed ends thereof. In such constructions a large quantity of the incoming draft air is directed along the longitudinal center line of the tuyère rows with the result that those portions become extremely active. A furrow thus forms along the center line of each tuyère row and the portions of the fuel bed adjacent these furrows become the most active parts of the fuel bed.

One object of the present invention is to provide an improved tuyère which functions in operation to increase the number of such active areas in the fuel bed and thus increase the burning rate of the stoker.

Another object is to provide a tuyère block which in operation is maintained at an extremely high temperature to prevent slag adherence thereto and which is so constructed as to deflect any slag coming into contact therewith into the adjacent retorts or toward the rear of the stoker.

Such a tuyère block construction is highly desirable, especially when fuels are burned having an ash content which fuses at relatively low temperatures. In the prior art constructions the molten ash flowing through the fuel bed congeals or solidifies when coming in contact with the relatively cold incoming air or the tuyère blocks, forming clinkers which not only clog the air openings therein, but which grow to such an extent as to impair the operation of the stoker. Such clinkers also cause considerable damage to the stoker parts. The present invention contemplates an improved construction which eliminates these undesirable conditions.

Other and further objects of the invention will become apparent as the description of the invention progresses.

Of the drawings:

Fig. 1 is a longitudinal sectional view taken through one of the retorts of an underfeed stoker.

Fig. 2 is a fragmentary plan view taken substantially along line 2—2 of Fig. 1.

Fig. 3 is a sectional view taken substantially along line 3—3 of Fig. 1, showing the condition of the fuel bed under operating conditions.

Fig. 4 is a plan view of one of the individual tuyère blocks.

Fig. 5 is a plan view of the tuyère block shown in Fig. 4 in inverted position.

Fig. 6 is a side view partly in section, showing the manner in which the tuyère blocks are assembled.

Fig. 7 is a fragmentary plan view of a modified tuyère block construction.

Referring to the drawings, the numeral 1 designates generally a furnace including in the present instance, a multiple retort underfeed stoker 10 2, comprising alternately disposed retorts 3 and tuyère rows 4. Fuel is fed to the retorts 3 from hoppers 5 by any suitable fuel feeding mechanism designated at 6, and a series of pushers 7 mounted in the bottom of the retort underfeed the fuel to extension grates 8, which in turn overfeed the residue to an ash pocket 9, extending transversely of the stoker between the lower end thereof and a bridge wall shown at 10. The individual tuyère blocks 4 may be composed of a highly refractory heat resistive material such as silicon carbide, or of any other suitable material. When the terms "front" and "rear" are employed in the description of the invention it is to be understood that the term "front" indicates those portions of the parts extending toward the front or fuel feeding mechanism 6 of the stoker, and "rear" indicates those portions extending toward the rear or bridge wall 10 of the furnace.

Referring to Figs. 4 to 6, it will be noted that each tuyère block 4 is of extremely rugged construction, and thus capable of withstanding the severe conditions of furnace operation. The top surface 11 of each tuyère block 4 has provided therein a depression 12, the side and rear walls 13 of which incline downwardly, and inwardly, as shown more particularly in Fig. 4. A series of slots 14 extend from depression 12 to the side edges 15 of each tuyère block through which draft air may pass. These slots are inclined slightly from front to rear of the block so that the air is directed into the fuel bed at a slight angle. These passages may be disposed normal to the direction of fuel movement but it has been found that better results are obtained by arranging the passages as herein shown. The nose portion 17 of each tuyère block inclines downwardly from front to rear thereof and is of substantially sinuous construction having a central groove 18 and outwardly and downwardly inclining side portions 19 and 20.

The under side 22 of each tuyère block 4 is also provided with a depression 23, the side and end walls 24 of which also incline downwardly and inwardly, as shown in Fig. 5, and a series 55

of slots 25 also extend from the depression 23 to the outer side edges 15 of the block through which draft air also may pass.

As shown in Figs. 5 and 6, each tuyère block 5 is also provided with a pair of inclined side edges 27 and 28 which in assembly rest upon the retort side plates 29. Also, when assembled on the stoker the substantially flat surface 22 of each tuyère block rests upon the upper flat surface 10 11 of the next lower tuyère of the series. A spacing element 30 provided intermediate the side edges 15 of each tuyère block 4 in assembly is adapted to abut against the forward edge 31 of the next lower tuyère block of the series, as 15 shown in Fig. 6.

Referring to Fig. 6, it will also be noted that the slots 14 and 25 are arranged in staggered relation, thereby causing a better distribution of the air emitted therethrough to the fuel bed. 20 Depressions 12 and 23 provided in the upper and lower surfaces respectively of each tuyère block 4 are open at their front ends, thus forming inlet passages for draft air entering the tuyères from the plenum chamber 32 provided beneath 25 the stoker. By this arrangement of air passages in the tuyère blocks no air is permitted to pass through the nose portion thereof and as a result it will become intensely hot during the operation of the furnace. In order to prevent damage to 30 the side plates 29 upon which the tuyère blocks 4 are supported, the inclined portions 27 and 28 of each tuyère block are provided with insulating portions 33, as shown in Fig. 3. Thus the heat absorbed by the tuyère blocks is retained 35 and not readily conducted to the metallic side walls 29 supporting the same.

By maintaining the nose portion of each tuyère block in this heated condition, it is apparent that any molten ash coming in contact therewith will not congeal but instead will remain in its molten state and as a result will flow down the central channel 18 toward the rear of the stoker or be deflected into the adjoining retorts by the inclined portions 19 and 40 20, depending upon what portion of the blocks the slag comes in contact with. Thus clinkers 45 can not form on the tuyère blocks and grow to such an extent as to impair the operation of the stoker. In the older constructions, especially when low grade coals are burned thereon, the molten ash congeals or solidifies when coming 50 in contact with the relatively cold incoming draft air or the tuyères and as a result clinkers form, which in many instances grow to such an extent as to impair the operation of the stoker. Considerable damage also results to the stoker 55 parts, which necessitates frequent delays in order that the damaged parts may be renewed. These undesirable occurrences are reduced to a minimum in the present construction. In order 60 to divert any molten slag away from the air openings 14 and 25, and thus prevent clogging thereof, a slag ledge 38 is provided at the sides of each tuyère block intermediate said openings.

The arrangement of air passages in the tuyère blocks as hereinbefore described, also results in the production of a more active fuel bed than is the case in the older constructions. As shown in Fig. 3, by emitting draft air to the fuel bed 65 from the sides of the tuyères only, the portion thereof adjacent the longitudinal center line of said tuyères receives but little air and consequently builds up. As a result the air flows upwardly as indicated by the arrows, and causes 70 furrows in the fuel bed to form longitudinally 75

thereof substantially along the side edges of the tuyère rows. Thus two such furrows for each retort are formed rather than a single one along the longitudinal center line of each tuyère row as is the case in the older constructions, and inasmuch as the portion of the fuel bed defining these furrows is constantly subjected to the incoming draft air a very active fuel bed results. 5

Under certain conditions it may be desirable to permit a small quantity of air to pass through 10 a portion of the nose end of each of the tuyère blocks. This may be desirable to control the temperature of the nose end. In this way the viscosity of the slag may be controlled. To this end slots 35 and 36 are provided in the upper 15 surface of the nose portion, as shown in the modified tuyère block 4' in Fig. 7.

From the foregoing description it is believed to be apparent that the present invention not only produces a more active fuel bed, thereby insuring better efficiency, but involves a construction which insures longevity of service. The highly refractory material of which the tuyère blocks are composed is well able to withstand the furnace temperatures and the blocks are so constructed as to effectively dispose of any molten ash coming in contact therewith, thereby insuring efficient operation of the stoker at all times. The individual tuyère blocks also present a novel construction which generally improves the operation 20 25 30 35 40 45 50 55 60 65 70 75 80 85 90 95 100 of the stoker as a whole.

While the embodiments herein shown and described are admirably adapted to fulfill the objects primarily stated, it is to be understood that the invention is not to be limited to those particular embodiments, since it may be embodied in other forms, all coming within the scope of the claims which follow.

What is claimed is:

1. A furnace tuyère block of approximately rectangular form, having when in operated position substantially flat vertical side surfaces, and substantially horizontal top and bottom surfaces, and being provided with passages for draft air extending along said top and bottom surfaces and inwardly from said side surfaces, a slag ledge projecting outwardly from each of said side surfaces and intermediate said top and bottom surfaces for diverting slag away from said passages extending along said bottom surface, and said tuyère block having a nose portion of substantially sinuous construction. 40 45 50

2. In a stoker furnace, the combination with alternately disposed fuel retorts and rows of tuyère blocks, of a rugged heat absorbing nose 55 portion on each of said tuyère blocks, the upper and lower surfaces of said nose portions, being substantially flat and in assembly, lying in abutting relation with adjacent tuyère blocks and presenting unbroken supporting surfaces to prevent 60 the passage of air between said nose portions, and said tuyère blocks being provided with passages for draft air extending along the top and bottom surfaces thereof, and inwardly of said side surfaces, said passages being disposed forwardly of said nose portions, and each of said nose portions having a central downwardly inclined groove forming with the grooves of adjacent tuyère blocks a channel extending over the length of the tuyère row for conducting molten 70 slag toward the rear of said stoker, and laterally extending and downwardly inclined slag diverting means provided at each side of said groove to divert the slag coming in contact therewith into said retorts. 75

3. A furnace tuyère block adapted for assembly with similar tuyère blocks in superimposed relation, said tuyère block comprising an approximately rectangular body portion having substantially flat top and bottom surfaces and vertical side surfaces and terminating at one end thereof in a rugged solid nose portion, said body portion being provided with passages for draft air extending along said top and bottom surfaces and inwardly from said side surfaces, said passages being disposed forwardly of said nose portion to prevent draft air from coming in contact therewith, whereby said nose portion is maintained extremely hot during operation of the furnace, and 5 slag diverting means provided on said nose portion, said slag diverting means comprising a central groove and downwardly inclined portions extending laterally of said groove.
4. A furnace tuyère block adapted for assembly 10 with similar tuyère blocks in superimposed relation, said tuyère block comprising a body portion having substantially flat top and bottom surfaces and vertical side surfaces, and a rugged solid nose portion, and being provided with passages for

draft air extending along said top and bottom surfaces and inwardly from said side surfaces, said passages being disposed forwardly of said nose portion to prevent draft air from coming in contact therewith, whereby said nose portion is 5 maintained extremely hot during operation of the furnace, slag diverting means provided in said nose portion comprising a downwardly inclined central groove, and transverse, downwardly extending portions on either side of said groove, and 10 a slag ledge extending laterally from each of said side surfaces for diverting slag away from said passages extending along said bottom surface.

5. A furnace tuyère block of approximately rectangular form, having, when in operative position, 15 substantially flat top and bottom surfaces and vertical side surfaces, and being provided with passages for draft air extending along said bottom surface and inwardly from said side surfaces, and means disposed above said passages and extending laterally of said side surfaces for diverting any slag away from said passages to prevent 20 clogging thereof.
